[57] CLAIM

The ornamental design for a combined grater and dispenser, as shown and described.

DESCRIPTION

FIG. 1 is a perspective view of a combined grater and dispenser showing my new design;

FIG. 2 is a top plan view thereof with the lid removed for clarity of illustration;

FIG. 3 is a right side elevation view of FIG. 2;

FIG. 4 is a left side elevation view of FIG. 2;

FIG. 5 is a bottom plan view of FIG. 2;

FIG. 6 is a top plan view thereof with the lid fitted;

FIG. 7 is a left side view of FIG. 6;

FIG. 8 is a left side view thereof with the lid slightly open;

FIG. 9 is a front elevation view of FIG. 2;

FIG. 10 is a rear elevation view of FIG. 2; and,

FIG. 11 is a perspective view thereof with the lid fitted.
